UNITED STATES PATENT OFFICE.

HERBERT R. BLISS, OF NIAGARA FALLS, NEW YORK.

SHIPPING CASE.

Application filed December 6, 1922. Serial No. 605,303.

To all whom it may concern:

Be it known that I, HERBERT R. BLISS, a citizen of the United States, residing at Niagara Falls, in the county of Niagara and

5 State of New York, have invented certain new and useful Improvements in Shipping Cases, of which the following is a specification.

This invention relates to method of sealing shipping cases constructed of fiber board or equivalent material and has for its purpose an improved constructed and sealed shipping case. The completed and sealed case has various features of advantage over 10 shipping cases heretofore constructed. For instance, the closure for the case is of such a character that on the top is presented four folded edges to the handler so that it is practically impossible to pick it up by the 15 flaps as is sometimes done and tear the fastenings or otherwise injure them.

Furthermore, the body of the case and the closure construction is of such a character that the same may be all made together 20 out of three blanks of such a character that no material whatever is wasted and a minimum amount of material is used in constructing the case and the closure.

In the drawings:

30 Fig. 1 is a perspective of the case.

Fig. 2 is a perspective of the case before it is completed by packing and sealing.

Fig. 3 is a section on the line 3—3 of Fig. 1.

35 Fig. 4 is a diagrammatic view showing the closure construction and the way in which the stitches are taken.

Fig. 5 is a section showing how stitches 1 to 10 are taken.

40 Figs. 6 to 8 inclusive show the blanks used for constructing one form of the case.

Fig. 9 is a perspective of a modified form.

The shipping case is constructed of three 45 separate blanks, the body blank which provides two sides *a*, the bottom *d* and the two cover wings *b* and *c*. The end blanks are designated *f* and *g*. *f* is provided with a cover wing *f'* and *g* is provided with a 50 cover wing *g'*. In one form of construction the fastening strips *h* are secured to three sides of the end blanks and these are right angularly folded over against the sides and part of the main body blank and fastened thereto by wire stitching. In the modified form of construction the fastening blanks

are secured to the main body blank and are folded over on to the end blanks and fastened thereto as shown in Fig. 9.

The closure is formed by folding in the 60 cover wings *b* and *c* as shown in Figs. 1 and 2 and then lapping the cover wings *f'* and *g'* over on to these. These cover wings *f'* and *g'* are separated from each other, which is necessary in order to permit the sealing 65 thru the slot formed at *j* to permit the withdrawing of the anvil in taking the stitches.

Now referring to Fig. 4 the way the stitches are taken will be shown. Two positions of the anvil are shown, one numbered 70 1 and the other 2. The anvil can be inserted over the wing *c* as shown in Fig. 4, and under the wings *f'* *g'* and *b* and may be swung around to take stitches 1, 2, 3, 4, 5, 6, 7, 8, 9, and 10. The number may vary to 75 suit the option of the operator and the stitches may be taken in varying order, the order shown being a convenient one. The anvil may then be inserted in the slot *j* being over the wing *b* and under the wing *c* 80 the stitches 11, 12, 13, 14, 15, 16, 17, 18, 19 and 20 may be then taken. This completes the closing of the case and the anvil may be withdrawn from the slot *j* formed by the 85 meeting edges of the wings *c* and *b*.

In this arrangement the anvil can be inserted and withdrawn without tearing the wings between which it passes nor requiring the cutting of hinge flaps to permit insertion or withdrawal of the anvil nor is a pasting 90 strip required over such hinging flaps.

I claim:

1. The method of sealing a three-blank fibre 95 shipping case having a body blank forming the bottom two side walls and opposed cover wings, and separate end blanks having opposed cover wings with two of the opposed cover wings abutting and the other two being separated, which comprises turning in first the abutting cover wings then turning in the separated cover wings over these, and then inserting a blade anvil in the slit left at the abutting edges of the abutting cover wings between the separated 100 cover wings and driving metallic fasteners along the free edges of the overlying cover wings above the underlying cover wing under which lies the blade anvil, the withdrawal of the anvil and the insertion on the other side of the box through the same slit 105 and the driving and clinching of metallic fasteners along the free edges of the overlying 110

ing wings above the other underlying cover wing, and finally the withdrawal of the anvil.

2. The method of sealing a fibre shipping case provided with a pair of abutting cover wings and a pair of cover wings short of abutting, which comprises the turning in first of the abutting cover wings, then the short cover wings, then inserting the anvil through the slit formed by the abutting cover wings and driving fasteners through the overlying cover wings and the under-

lying cover wing at one side of the case, the withdrawing of the anvil and the insertion of the anvil in at the opposite side 15 of the case through the same slit at the center of the case in the space between the edges of the two overlying cover wings, and finally the driving of fasteners through the overlying cover wings and the other 20 underlying cover wings at such side of the case.

In testimony whereof I affix my signature,
HERBERT R. BLISS.
